UNITED STATES PATENT OFFICE

159,165

NEWSPAPER RACK OR SIMILAR ARTICLE

Henry F. Rippe, Cincinnati, Ohio

Application October 8, 1948, Serial No. 149,025

Term of patent 3½ years

(Cl. D80—9)

To all whom it may concern:

Be it known that I, Henry F. Rippe, a citizen of the United States, residing at Cincinnati, in the county of Hamilton and State of Ohio, have invented a new, original, and ornamental Design for a Newspaper Rack or Similar Article, of which the following is a specification, reference being had to the accompanying drawings, forming part thereof.

The figure is a perspective view of a newspaper rack or similar article showing my new design.

I claim:

The ornamental design for a newspaper rack or similar article, as shown.

HENRY F. RIPPE.
